UNITED STATES PATENT OFFICE.

GEORGE KOHLHAAS, OF ELMIRA, NEW YORK.

DIE AND DIE-HOLDER.

1,250,323.

Specification of Letters Patent.

Patented Dec. 18, 1917.

Application filed October 26, 1915. Serial No. 58,005.

To all whom it may concern:

Be it known that I, GEORGE KOHLHAAS, citizen of the United States, residing at Elmira, N. Y., have invented certain new and useful Improvements in Dies and Die-Holders, of which the following is a specification.

My present invention is an improvement upon that disclosed in an application for 10 Letters Patent of the United States filed by me January 31, 1914, #815,786, and my present improvements relate more particularly to simplified means for adjusting the cutting dies, and clamping them in the desired positions.

Another feature of the present invention relates to the formation of the dies by which they will all readily clear themselves of the cuttings or chips.

20 Further features of the invention will be disclosed hereinafter.

In the accompanying drawings

Figure 1 is a sectional view of the tool with my improvements embodied therein;

25 Fig. 2 is a face view of the complete tool; Figs. 3 and 4 are face views of the gage ring and clamping nut respectively;

Fig. 5 shows one of the cutting dies;

30 Fig. 6 is a rear view of the die carrying block;

Fig. 7 is a view of a coupling piece;

Fig. 8 is a face view of the shank head.

In these drawings, 1 indicates the shank of the tool adapted to be connected with the 35 driving spindle in any suitable manner. This shank has a head 2 provided with a concaved face formed substantially like the segment of a sphere. From this concaved face two pins 3 project into radial slots or 40 openings 9 in a coupling piece or compensating member 8 which has a convex face corresponding in curve or sphericity to the concaved face of the flange or head 2. This compensating piece also receives pins 10 projecting from the concaved face 7 of the die carrying piece 4. This die carrying piece is held to the head or flange 2 by a hub or cap piece 11, which is provided with a flange 12 overlapping the flange 6 of the die 50 carrying piece, the said hub being secured to the head or flange 2 by a screw or bolt 13. The die carrying piece 4 projects forwardly through the opening within the flange 12, and this projecting portion is 55 threaded, as at 5, and the face of this die carrying piece is provided with inserted

pieces 26 which serve as guides for the dies 15, which dies are provided on their rear faces with grooves to fit the guide ribs. The dies, on their outer faces, are beveled, and 60 surrounding the dies there is a gage ring 19. This gage ring or nut is threaded on its interior to engage the threads 5 of the piece 4, and by turning this gage piece or nut its plain beveled face 18 is adjusted in respect 65 to the beveled outer face of the dies, and thus the position of the dies may be regulated in respect to each other, said dies backing up against the beveled inner face of the gage ring, which, according to the adjustment of 70 the gage ring, will set the dies closer together or farther removed from each other as may be desired. In my previous application the dies were clamped in position to which they were adjusted by nuts bearing against their 75 faces, said nuts being carried by bolts or pins screwed into the die carrying piece 4, and passing through openings in the dies. This construction necessitated a separate nut and pin for each die section, and each die or 80 section had to be provided with an opening for the pin or bolt, and if there were four dies it required four adjustments, one for each bolt or nut, in order to clamp the four dies in place. Furthermore, the perforating 85 of the dies to receive the pins not only increased the cost of manufacture, but rendered the dies liable to warp in hardening. In order to avoid this construction, I employ a clamping nut A, which is threaded 90 on its interior and is fitted to the exterior threads B of the gage ring 19. This nut is provided with a cylindrical portion a, and an inwardly extending flange or face portion c which overlies the front faces of the dies 95 and securely clamps them in the positions to which they may be adjusted, and this nut also serves to lock the gage ring against displacement on the die carrier 4. It will be observed that by turning this nut A all of 100 the dies will be clamped at one action, and simultaneously the gage ring will be locked in place.

My present improvement also concerns the formation of the dies themselves.

In the formation of the sectional die I employ a milling instead of a drilling operation for the gullets or radial openings or recesses d. A number of the sections can be milled at one operation to form these 110 gullets or half circular recesses, and where four sections are employed a gang of eight

milling cutters may be used. The sections, when placed together, provide the recesses or gullets as shown in Fig. 2, which, if drilled in the die block, would have to be done before the block is split. Further by the milling operation the front end of the gullet at d' can be milled deeper than at the rear or inner end of the die section, this providing, when the die sections are brought together, recesses d which flare toward the front and thus provide for the escape of chips and prevent the die from clogging.

I do not limit myself to the particular arrangement of the clamp nut and gage ring described and shown except as called for by the appended claims.

I claim as my invention:

1. In combination with the die block screw threaded externally, a plurality of dies at the front thereof, a gage ring having an internal thread engaging the external thread of the die block, and having a conical inner face to engage the conical outer faces of the sections, and a locking nut engaging an external thread on the gage ring and having a portion engaging the dies to clamp the same in place, substantially as described.
2. In combination with a die block having an exterior cylindrical screw-threaded portion, a gage ring having an internal thread engaging the external thread of the

die block and having means to variably determine the positions of die sections, said gage ring having an external screw thread, 35 die sections within the gage ring and having their front faces in a plane substantially at right angles to the axis of the gage ring, and a locking nut engaging the external screw thread of the die block and having a flange extending inwardly at right angles to its axis to bear on the front faces of the die sections, substantially as described.

3. In combination a die block, die sections, a ring portion surrounding the die sections having means for variably determining the positions thereof, and a clamping nut screw-threaded upon said ring portion and having a front flange to bear on the faces of the dies for clamping them in position.

4. In combination a die holder and a die composed of sections divided from each other on lines parallel with the axis of the die, each of said sections having a cutting portion with a gullet at each side of the cutting portion, said gullets being deeper at the front than at the rear of the sections, the gullets of adjacent sections matching each other and providing recesses flaring toward the front of the die, substantially as described.

In testimony whereof, I affix my signature.

GEO. KOHLHAAS.
